(57) **CLAIM**

The ornamental design for a motorized mobile system controller and sensor housing, as shown and described.

DESCRIPTION

FIG. 1 is a perspective view of a motorized mobile system controller and sensor housing showing our new design, the motorized mobile system controller and sensor mounted on a motorized mobile system in the form of a wheelchair. FIG. 2 a top isometric view of the motorized mobile system controller and sensor housing showing our new design. FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof; and,

FIG. 9 is a bottom isometric view thereof.

The broken lines in the Figures show environment or portions of the motorized mobile system controller and sensor housing that form no part of the claimed design. The shade lines in the Figures show contour and do not claim surface ornamentation or treatment.
